PRINTED FORM

Daniel L. Francescon, Oak Park, Ill., assignor to
 Columbian Bank Note Company, a corporation
 of Illinois

Application February 27, 1942, Serial No. 432,546

2 Claims. (Cl. 282—23)

This invention relates to an improved printed form, and more particularly to a form which is provided with an adhesive face but may nevertheless receive subsequent inscriptions before being permanently attached to solid material, such as a piece of glass or the like.

The primary object of the invention is to provide an improved form which is adapted for use as an automobile license validation certificate. The certificate may be made up in a multiple copy set provided with interleaved carbon and inserted in a typewriter for subsequent inscriptions, or manually written. All of the forms may be numbered by a printing operation after the forms have been brought into registration in a set.

The invention is illustrated in a preferred embodiment, in the accompanying drawing, in which—

Figure 1 is a plan view of a set of forms embodying the invention with the corner of the top form and adjacent carbon curled upwardly to show an underlying sheet; and Figure 2, a side elevational view of the same.

In the embodiment illustrated, a top sheet 3 is superposed on stationery sheets 4. Each of the stationery sheets is provided with a top detachable margin 5. Transfer or carbon sheets 6 are interleaved between the stationery sheets and are secured together by the binding strips 5. Preferably, the carbon sheets are somewhat shorter in length than the carbon strips so that the stationery sheets may be detached from the carbons by gripping them at their lower edges and drawing them sharply away from the binding margin 5.

The top sheet 3 is preferably a steel engraving which may be provided with an underlying safety tint to prevent any attempted erasure or alteration. The form has a number of blank areas 7 to receive subsequent inscriptions. Preferably, the sheet is of a good grade of thin paper, and after printing, is treated with a suitable resinous varnish to make it water repellent. In order that this top sheet may form a certificate which may be secured to the windshield of a car, the face of the sheet, except over the inscription receiving areas, is coated with a suitable spirit adhesive which may be applied by the silk screen method. The inscription receiving areas are kept clear of adhesive because any writing or typewriting done on the adhesive would not be permanent after the adhesive is moistened for application to a windshield.

In order to avoid any chance for errors in the underlying copies of the certificate, a serial number, as indicated at 8, is printed on the set of forms as the last step. This number may be printed in an adhesive coated area by means of a special penetrating ink which penetrates the adhesive. The printing operation will also cause the identical number to be printed on the underlying sheets by the impression transmitted through the transfer or carbon sheets.

The present form may be used as a validation certificate to take the place of metal license plates and may be used in a State in which various counties issue such certificates. The form may be inserted into a typewriter and the usual information concerning the applicant may be typed in. Also, if desired, the licensee may sign the form in a suitable space, as indicated at 9. The certificate may also be countersigned, as indicated at 10, by the agent for the tax commission. Upon payment of the required fee, the applicant is given the top sheet to be moistened and applied to the windshield of his car, and the underlying copies, after being detached from the binding strip, may be filed by the taxing authorities numerically or alphabetically.

The foregoing detailed description has been given for clearness of understanding only, and no unnecessary limitations should be understood therefrom for some modifications will be obvious to those skilled in the art.

I claim:

1. A printed form comprising: a paper sheet printed to provide blank areas to receive subsequent inscriptions, a varnish coating on said sheet to render it water repellent, and an adhesive coating covering the face of said sheet except said inscription receiving areas.

2. A multiple copy set comprising: a plurality of stationery sheets and interleaved transfer sheets bound together at one marginal portion, said top sheet being printed to provide blank areas to receive subsequent inscriptions and having an adhesive coating over all of the face of said top sheet except over said blank areas, and registered indicia printed on the assembled stationery sheets by means of adhesive penetrating ink on the top sheet and by means of the transfer sheets on the underlying sheets.

DANIEL L. FRANCESCON.
